(57) **CLAIM**

We claim the ornamental design for a hose reel, as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom perspective view of an embodiment of the claimed design;

FIG. 2 is a top perspective view thereof;

FIG. 3 is a top view thereof;

FIG. 4 is a front view thereof;

FIG. 5 is a rear view thereof;

FIG. 6 is a left side elevation view thereof;

FIG. 7 is a right side elevation view thereof;

FIG. 8 is a bottom perspective view of another embodiment of the claimed design;

FIG. 9 is a top perspective view thereof;

FIG. 10 is a top view thereof;

FIG. 11 is a front view thereof;

FIG. 12 is a rear view thereof;

FIG. 13 is a left side elevation view thereof; and,

FIG. 14 is a right side elevation view thereof.

Any portion of the article depicted in broken lines forms no part of the claimed design. Broken lines formed by equal length dashes show unclaimed subject matter.
